UNITED STATES PATENT OFFICE.

EDWARD H. MOYLE, OF LOS ANGELES, CALIFORNIA, ASSIGNOR OF ONE-HALF TO OSCAR M. SOUDEN, OF LOS ANGELES, CALIFORNIA.

BILL IRONER AND STERILIZER.

Application filed August 12, 1920. Serial No. 402,963.

To all whom it may concern:

Be it known that I, EDWARD H. MOYLE, a citizen of the United States, residing at Los Angeles, county of Los Angeles, State 5 of California, have invented certain new and useful Improvements in Bill Ironers and Sterilizers, of which the following is a specification.

This invention relates to improvements in 10 machines for cleansing and smoothing articles such as paper money; but particularly relates to machines for ironing out and sterilizing such articles. Although I describe my invention particularly as applied to paper currency, it will be readily understood 15 that the invention is not necessarily limited to such articles, but may be applied to other articles of a similar nature which may need ironing out and sterilizing from time to time.

In the normal use of paper currency it becomes soiled and wrinkled. It loses its stiffness and after a short time in actual circulation it becomes limp, and this limpness 25 increases its liability to folding, creasing and bending, and also increases its liability to being torn or otherwise mutilated. It is a general object of my present invention to provide a simple and effective machine for 30 so treating such paper currency as to preserve its original stiffness; and at the same time to sterilize it so as to prevent the carrying of disease germs and other filth. Although my machine, in itself, provides only 35 a means for smoothing out and sterilizing the bills, it will be readily understood that, prior to or subsequent to the action of my machine the bills may be run through a washing bath, or may be in any other suitable manner treated to remove surface dirt, etc. But, whether or not the bills are thus 40 cleansed, my machine gives them their pristine freshness and smoothness of appearance and sterilizes them so as to prevent carrying 45 of bacteria, etc.

It is an object of my invention to provide a simple, compact and effective machine, simple in operation, and of large capacity. It is also an object to provide a machine 50 suitable to be used in banks and other institutions, so that the ironing and sterilizing may be carried on by individual banks, or even if needed by individual tellers as they pass out paper currency.

With these objects in view the further ob-

jects corresponding features of my invention will be best understood from the following detailed description of preferred and specific forms of device embodying the invention; this description being given not for the purpose of limiting my invention to the specific forms described, but for the purpose of giving a clear and comprehensive understanding of the invention both in its broad aspect and in its preferred and specific details. For the purpose of this specific description, I refer to the accompanying drawings, in which—

Fig. 1 is a plan of the machine, with parts shown in section to show the main working parts; Fig. 2 is a longitudinal sectional view taken as indicated by line 2—2 on Fig. 1; Fig. 3 is an enlarged longitudinal section through one of the heated rolls; Fig. 4 is an enlarged transverse sectional view taken as indicated by line 4—4 on Fig. 2; and Fig. 5 is an enlarged longitudinal section showing a somewhat modified form of a heated roll.

Throughout the drawings numeral 10 designates a suitable base upon which the machine is mounted. The machine primarily consists of a group of rolls arranged in pairs and with at least one of each pair of rolls heated to a comparatively high temperature. The rolls are preferably contained in a suitable case 11. It will be readily understood that any number of pairs of rolls may be used, but I have shown two pairs in the drawings.

The upper rolls R are preferably carried in bearing blocks that may be moved up and down by adjusting means extending through the case 11. This feature allows a certain amount of adjustment to be made so the distance between the rolls of a pair of rolls may be varied. The upper rolls R are preferably carried in bearing blocks 12, which are provided with bushings 13 within which shafts 14 rotate. Bearing blocks 12 are adjustable in a vertical plane by means of screws 16, which are supported by the top of case 11 and extend downward therefrom and screw-threadedly engage bearing blocks 12. Collar 17 is adapted to be set on screw 16, thereby limiting the upward vertical travel of the screw which would otherwise tend to slip upwardly when a bill was passed between the rolls. To further hold this vertical adjustment clamp screw 18 is 110

provided which is carried in a slot 19 in the end wall of the case 11. After the desired adjustment has been obtained, clamp screw 18 is tightened and furnishes a permanent holding means for the bearing block 12. By referring to the drawings it will be seen that there are duplicate bearing blocks 12 and corresponding adjustments on both sides of each of the sides of the upper roll. 10 Shafts 14 are provided with end-thrust collars 20 which abut against the inner sides of bearing blocks 12. Bushings 21 and shafts 15 support the heating elements in two of the rolls. The two upper rolls R are 15 adjustably supported as described; it is not necessary that the two lower rolls R be adjustably supported, so accordingly they are mounted in bearings which are the same as those before described except that the bearing blocks 12^a are in this case fixed with reference to the case 11, preferably integral with the case.

It will be noted from the drawings that one roll of each pair is provided with heating means and that this is preferably the upper roll of one pair and the lower roll of the other pair. By this arrangement I give a bill two successive ironings and heatings, with heat applied directly to both sides of 20 the bill, and at the same time use only two heating elements. The two rolls that have the heating means have their shafts 14 hollow to carry bushings 21 and shafts 15 to support the heating elements; and although 25 it is not necessary I have shown the other two rolls similarly equipped and the shafts 15 and bushings 21 in place, so that the heating elements can be put into those rolls also, if desired. Bushings 21 is placed between hollow shaft 14 and stationary shaft 15. The stationary shaft 15 is held in place by means of nuts 22; and the bushings 21 may either fit the hollow shaft with a running fit, or there may be an open space between the bushing and shaft 14.

It is preferred that rolls be driven from one central shaft 23 but they may however, be driven in any suitable manner. I have shown the shaft as passing through the machine and supported in bearings 24 formed on the side wall of the case. One end of this shaft passes beyond the side wall and connects to a suitable coupling 25, which coupling is connected to the shaft of a typical motor 26 from which the power is derived. It will be readily understood that the machine may be driven in any suitable manner and is not in any way limited to this particular type of driving means.

60 As will be noted in Figs. 2 and 4 the rolls are driven in pairs and in opposite directions, so that the bills may be fed into the machine and the first pair of rolls will then feed the bill into the next successive pair, 65 which then passes it outward and beyond the

case. To permit feeding the bills into the machine and then gathering them after being treated, two slots or openings are arranged in the case 11. The entrance opening is provided with a substantially flat bottom 27 formed as a part of case 11 and extending out from the case far enough to allow several bills to be stacked ready to be inserted in the machine. This shelf or holder may be provided with suitable side plates 70 28. Bottom 27 passes within the case 11 and extends right up to the first pair of rolls to prevent the bills from falling before they engage the lower roll. A curved projection 29 extends inwardly and guides the bills into the first pair of rolls. Back of the last pair of rolls are somewhat similar projections. The upper projection 30, however, is made adjustable so that the distance 75 between itself and the lower shelf 27^a may be varied. This adjustment is obtained by means of screws 31 which are carried in slots formed in a side wall of the case, and are screw threadedly engaged to the projection 80 30. The outward extending portion of the lower projection 27^a is somewhat shorter than that of the extending shelf 27. Guide plates 32 are arranged above and below the line of movement of the bills. These plates are held concentric with shafts 14 by supporting portions 33 which loosely fit these shafts at the ends of the rolls. Plates 32 are secured to portions 33 by means of screws 85 32^a. These plates are arranged so as to extend between the rolls and parallel to the axis of the rolls and to fit loosely but snugly between the upper rolls and likewise with the lower rolls. There are two of these plates 32, one between the lower rolls R and one between the upper rolls R. This feature 90 prevents the bills from tending to cling to the rolls and revolve with them.

It is preferred, for mechanical conveniences, that each pair of rolls be driven at the opposite end to that which the other pair is driven. Upon shafts 14 are gears 34 which mesh with each other and cause the lower shaft to drive the upper shaft in each pair. Near gear 34 and upon the lower shaft 14 of each pair is a slightly larger gear 35 which meshes with pinion 36 secured to drive shaft 23. All the upper and lower rolls are thus driven in the proper direction to feed the bills through the machine. It is preferred that the bills be fed 100 through the machine lengthwise, and this aids in feeding the bills through the rolls, in that the maximum length assures one pair or both pairs of rolls constantly pulling 105 the bills forward.

As was stated hereinbefore, at least one upper and one lower roll is to be heated to directly heat both faces of the bills, and I prefer to heat the upper roll of one pair and the lower roll of the other pair so that the 110 115 120 125 130

bills will be heated simultaneously with each pressing. The heating means are supported on shafts 15, which are stationary. These shafts are provided at each end with bushings 21; around which hollow shafts 14 rotate. Shafts 14 are provided at their inner ends with enlarged portions or flanges 37 which are adapted to carry the cylindrical member 38. Flanges 37 furnish the end walls and member 38 furnishes the circular side walls of the rolls. Within the hollow roll thus formed, and carried by stationary shaft 15 is the heating element. The heating element consists of resistance wire 39 coiled around a suitable insulating tube 40. This insulating tube may be made of any insulating material that is adapted to withstand comparatively high temperature. It is preferred that insulating tube 40 be carried on member 41 which is force fitted on shaft 15. Member 41 is preferably provided with a suitable depression on its outer surface to hold the insulating tube 40. Also member 41 is provided with an inner recess 41^a to permit the lead wires 39^a to enter a suitable bore 42 in shaft 15. Lead wires 39^a extend outwardly and beyond the end of shaft 15 to a suitable source of current. It will be readily understood that the wires, either in the coil or the lead wires, do not revolve, and that the member 41, carrying with it the heating coil, may be easily removed in a unit. The heating element remains stationary and the outer tube member rotates and is heated from this heating coil which is arranged near the peripheral member 38 of the roll so that the maximum amount of heat is obtained from the heating coil. The insulating tube 40 may be also of heat insulating material while the outer peripheral tube 38 of the roll is of heat conducting material. The heat is thus radiated and conducted efficiently outwardly and is not dissipated inwardly. Member 41 may also be of heat insulating material (such as fibre or the like) to aid in this purpose. It is preferred that a heat insulating compartment 44 be provided which will entirely enclose the rolls, the only openings being where the bills are fed in the machine and where they are discharged. This heat insulating compartment 44 may be surrounded by a double-wall structure 50, packed with a non-conducting material 51, which will hold the heat within the chamber.

The case 11 may be provided with a removable cover 43 which permits accessibility to the parts.

In the foregoing I have described a form of device in which the heating coil is stationary within the rotating roll. I now describe a form in which the heating coil may rotate with the roll. The heating element 39^a, 40^a in this case revolves with the rotating shaft 14^a and the roll itself. The tube mem-

ber 38^a of the roll is substantially the same in formation as member 40, but of course, the hollow shaft is eliminated, in this case, and the end wall 37^a is formed with suitable bosses which fit around and are keyed or otherwise secured to shaft 14^a. In order to furnish connection for the heating element two circular rings 45 are provided, which are continuously in contact with screws 46 which serve as brushes. Screws 46 are screw-threadedly engaged to insulating bushings 47 which are secured to upright 49, which may be made a part of the case 11. Suitable lead wires make connection between the screws and the source of power.

In either form of device a thermostatic heat control may be used. For instance, as shown in Fig. 2, a thermostat switch 60 may be inserted through the top wall of the case. One of the feed wires may lead to this device, which may be of any usual construction and which may be, as is well known in the art, adjustable to break the circuit at any desired temperature to prevent overheating of the device.

Having described a specific preferred form of the present invention, I do not wish to limit myself to these details of construction, but wish to reserve to myself any changes, modifications, or variations that may appear to those skilled in the art or fall within the scope of the following claims.

Having described a preferred form of my invention I claim:

1. In combination, a frame, two parallel pairs of parallel rolls revolvably mounted on the frame, the rolls of each pair being adjustable toward peripheral contact with each other along longitudinal lines of contact, the planes of the axes of each pair of rolls being transverse to the plane determined by the two said lines of contact, one roll of each pair, being rolls located on opposite sides of the last mentioned plane, being hollow, and heating means within the hollow rolls, the peripheral walls of the rolls being of heat conducting material and the heating means being close to the peripheral walls.

2. In combination, a frame, two parallel pairs of parallel rolls revolvably mounted on the frame, the rolls of each pair being adjustable toward peripheral contact with each other along longitudinal lines of contact, the planes of the axes of each pair of rolls being transverse to the plane determined by the two said lines of contact, one roll of each pair, being rolls located on opposite sides of the last mentioned plane, being hollow, and heating means within the hollow rolls embodying an annular electric heating element close to the peripheral wall of the roll, a stationary shaft extending through the hollow roll, a heat insulating member surrounding the shaft and supporting the heating element, and the peripheral

wall of the roll being of heat conducting material.

3. In combination, a frame including a heat insulating casing, a pair of rolls within the casing, means to direct articles through the casing and between the rolls, one of the rolls being hollow and its peripheral wall being of heat conducting material, a heating element within the hollow roll close to its peripheral wall, and a heat insulating member within the heating element.

4. In combination, a frame embodying a heat insulating casing, two parallel pairs of parallel rolls revolvably mounted in the casing in bearings thereon, the bearings of one roll of each pair being adjustable to adjust one roll of each pair toward peripheral contact with the other roll of the pair, the planes of the axes of each pair of rolls being transverse to the plane determined by the said lines of contact, one roll of each pair, being rolls located on opposite sides of the last mentioned plane, being hollow, hollow trunnions for the two hollow rolls, a stationary shaft extending through the hollow trunnions and rolls, a mounting member of heat insulating material on each shaft within the hollow roll, an annular heating element around said member close to the peripheral wall of the roll, which peripheral wall is of heat conducting material; and means to rotate the pairs of rolls to feed an article between them.

5. In combination a frame embodying a heat insulating casing, two parallel pairs of parallel rolls revolvably mounted in the casing in bearings therein, the bearings of one roll of each pair being adjustable to adjust one roll of each pair toward peripheral contact with the other roll of the pair, the planes of the axes of each pair of rolls being transverse to the plane determined by the two said lines of contact, one roll of each pair, being rolls located on opposite sides of the last mentioned plane, being hollow, hollow trunnions for the two hollow rolls, a stationary shaft extending through the hollow trunnions and rolls, a mounting member of heat insulating material on each shaft within the hollow roll, an annular heating element around said member close to the peripheral wall of the roll, which peripheral wall is of heat conducting material; means to guide articles between the rolls embodying members lying on opposite sides of the last mentioned plane and supported at their ends upon the rolls.

6. In combination, a frame embodying a heat insulating casing, two parallel pairs of parallel rolls revolvably mounted in the casing in bearings thereon, the bearings of one roll of each pair being adjustable to adjust one roll of each pair toward peripheral con-

tact with the other roll of the pair, the planes of the axes of each pair of rolls being transverse to the plane determined by the two said lines of contact, one roll of each pair, being rolls located on opposite sides of the last mentioned plane, being hollow, hollow trunnions for the two hollow rolls, a stationary shaft extending through the hollow trunnions and rolls, a mounting member of heat insulating material on each shaft within the hollow roll, an annular heating element around said member close to the peripheral wall of the roll, which peripheral wall is of heat conducting material; a drive shaft parallel to and spaced equidistantly between the sets of rolls; gears interconnecting the rolls of each pair, pinions on the drive shaft one at each of the roll ends, a gear on a roll of one pair at one end meshing with one pinion, and a gear on a roll of the other pair at the other end meshing with the other pinion.

7. In combination, a frame embodying a heat insulating casing, two parallel pairs of parallel rolls revolvably mounted in the casing in bearings thereon, the bearings of one roll of each pair being adjustable to adjust one roll of each pair toward peripheral contact with the other roll of the pair, the planes of the axes of each pair of rolls being transverse to the plane determined by the two said lines of contact, one roll of each pair, being rolls located on opposite sides of the last mentioned plane, being hollow, hollow trunnions for the two hollow rolls, a stationary shaft extending through the hollow trunnions and rolls, a mounting member of heat insulating material on each shaft within the hollow roll, an annular heating element around said member close to the peripheral wall of the roll, which peripheral wall is of heat conducting material; means to rotate the rolls, and means to guide articles between the rolls embodying members lying on opposite sides of the last mentioned plane and supported at their ends upon the rolls.

8. In a device of the character described, two pairs of parallel rolls arranged in substantially quadrilateral formation when viewed from their ends; shafts for the rolls projecting from their ends, bearings for the shafts, and guide means to guide an article across the space between the pairs of rolls embodying a pair of guide members each lying close to a roll of each pair, and supporting means for the guide member at their ends embodying extensions which engage around the roll shafts.

In witness that I claim the foregoing I have hereunto subscribed my name this 6th day of August 1920.

EDWARD H. MOYLE.
